UNITED STATES PATENT OFFICE.

BERTRAND P. KENYON, OF GRAND RAPIDS, MICHIGAN, ASSIGNOR TO THE SHAW WALKER COMPANY, OF MUSKEGON, MICHIGAN, A CORPORATION OF MICHIGAN.

CARD-INDEX DRAWER.

No. 873,755.

Specification of Letters Patent.

Patented Dec. 17, 1907.

Application filed March 23, 1907. Serial No. 364,032.

To all whom it may concern:

Be it known that I, BERTRAND P. KENYON, a citizen of the United States of America, residing at Grand Rapids, in the county 5 of Kent and State of Michigan, have invented certain new and useful Improvements in Card-Index Drawers; and I do hereby declare the following to be a full, clear, and exact description of the invention, such as 10 will enable others skilled in the art to which it appertains to make and use the same.

My invention relates to improvements in card index drawers, and more particularly to the means for operating the locking rod 15 for securing the cards within the drawer, and its object is to provide means for moving the rod vertically to and from a position below the plane of the upper surface of the bottom of the drawer to a position within 20 the upper part of the opening in the cards, said movement being vertical and edgewise, and then turning the rod to a horizontal position within the openings to secure the cards in place, and in various features of construction and arrangement, as will more fully appear by reference to the accompanying drawings, in which:

Figure 1. is a plan view of a card index drawer with my device therein; Fig. 2. an enlarged detail in elevation of the mechanism at the front end of the rod with the rod in elevated position; Fig. 3. the same of the mechanism at the rear end of the rod; Fig. 4. the same as Fig. 2. with the rod in lowered position; Fig. 5. the same as in Fig. 3. with the rod lowered; Fig. 6. a detail of the rod operating mechanism shown in elevation from the direction opposite Figs. 2 and 4; and, Fig. 7. a vertical section of the same in a plane at 40 right angles to Fig. 6.

Like numbers refer to like parts in all of the figures.

1—1 represents bottom plates of the drawer, spaced apart at the middle and between which are rods 2 and 3 within the plane of the bottom and near the respective edges thereof. These rods serve as guide rods for the back rest 20, and one also serves as a rock shaft as hereafter described. Midway between these rods and centrally of the drawer is a flat locking bar having a journal 7 at each end midway of its edges. Secured to the respective ends of the drawer are plates 5 and 6 each provided with a vertical slot 15 in which the journals 7 are vertically

movable and rotative. To raise and lower the journals in the slots in the plates 5 and 6, one of the round rods (3 in this case) is made rotative thus forming a rock-shaft to the respective ends of which are rigidly attached 60 arms 8 and 9 having slotted openings in their movable ends in which are inserted the journals 7 on the ends of the locking bar 4. The rock-shaft thus serves to connect these arms and move the same simultaneously to 65 raise and lower the locking bar 4. To accomplish this movement, I provide a handle having a shank 19 extending through the front of the drawer and rotative therein on the inner end of which is mounted a crank 70 wheel 16 having a crank pin 17 on which pin is journaled a connecting rod 18 extending downward and connected to the end of the journal 7 of the locking bar 4. By rotating this handle, the end of the bar 4 will be raised 75 and lowered and the arms will be moved simultaneously and thus carry the locking rod up and down in the slots 15.

To limit the rotation of the crank wheel 16 to the upper and lower positions of this bar, 80 the connecting rod 18 is off-set laterally from the crank-pin, one-half the diameter of the shank 19 and engages the same at the upper and lower dead center of the movement of the crank pin, thus limiting the movement 85 of this wheel 16 to one-half revolution. To turn the locking bar 4 from vertical to horizontal position and hold the same and also to turn the bar to vertical position as it descends, a forked or toothed member 12 is 90 rigidly secured to the inner end of the shank 19 and engages a substantially similar member 13 rigidly secured to the locking bar 4 and in the same plane. Thus as the bar rises during the last portion of its movement, 95 these members 12 and 13 engage in a manner analogous to gear teeth and turn the bar 4 one-fourth of a revolution upon its journals and remain interlocked to hold the bar from turning in either direction as shown in Fig. 2. To guide the bar 4 in vertical position as it rises and falls in the slots, a vertical guide 14 extends alongside of the slot 15 in the plate 6 and slidably engages the flat side of the locking bar and thus prevents it from 105 turning upon its axis during its vertical movement in the slots.

In operation, by turning the shank 19 one-half revolution, the rod is carried upward from below the plane of the upper sur- 110

face of the bottom to proper locking position within a keyhole slot in the cards, (not shown) and then turned to horizontal position and held from further movement, thus 5 securely locking the cards in the drawer. A reverse one-half revolution of the shank 19, turns the locking bar to vertical position and then carries it downward vertically and edgewise to below the plane of the upper 10 surface of the bottom. When in this position, the bar is wholly beneath the plane of the cards, and cards having no openings therein, can be used in the drawer, if so desired.

It will be noted that the rod moves vertically 15 and edgewise until it has reached its upper position. It may thus be used with cards having very narrow keyhole slots in their lower edge to receive the same, thus using but little of the card surface to form 20 the slot.

What I claim is:

1. In a card index drawer, a rock-shaft, parallel arms rigidly attached to the rock-shaft, a flat locking bar journaled in the arms 25 and carried thereby, means for raising and lowering the arms, and means for rotating and holding the bar.

2. In a card index drawer, vertically slotted plates, a flat locking bar having journals 30 on its ends traversing the slots and rotative therein, a rock-shaft, parallel arms rigidly attached to the rock-shaft and having slots to receive the journals of the bar, means for raising and lowering the arms and means for 35 turning and holding the bar.

3. In a card index drawer, a rock-shaft, parallel arms rigidly attached to the rock-shaft, a manually rotated crank wheel, a rod connected to the wheel and to one of the 40 arms, and a locking rod supported and adjusted by the arms.

4. In a card index drawer, a drawer, a vertically slotted plate attached to each end of the drawer, a flat locking bar, journals on 45 the ends of the bar and traversing the slots in the plates and rotative therein, a rock-shaft, slotted arms rigidly attached to the respective ends of the shaft and engaging the journals of the bar, a knob having a shank journaled in the end of the drawer, a crank rotated by the shank, and a rod connecting the crank and one of the journals of the bar.

5. In a card index, a rock shaft, arms 55 rigidly attached to the respective ends of the shaft, a flat locking bar having journals rotative in the arms, a knob having a rotative shank, a crank mounted on the shank and rotated thereby, a rod journaled on the 60 crank and offset laterally and also extending above and below the crank to laterally engage the shank, the lower end of the rod also being connected to one of the arms to raise and lower the bar.

6. In a card index, a drawer, plates attached to the respective ends of the drawer and having vertical slots, a flat locking bar having journals traversing the slots and rotative therein, a guide on one plate adapted to slidably engage a flat side of the bar, means for raising and lowering the bar in the slots, and means for turning the bar to a horizontal position when its journals are in the upper ends of the slots.

7. In a card index drawer, a vertically movable and rotative flat locking bar, means for raising and lowering the bar, a knob having a rotative shank, and interlocking members on the shank and bar respectively, whereby the bar is rotated and held when in raised position.

8. In a card index drawer, a rock-shaft, arms fixed on the rock-shaft, a flat locking bar journaled in the arms and supported thereby, a knob having a rotative shank, 85 interlocking members fixed on the shank and bar, whereby the bar is rotated and held, a crank on the shank, and a rod connected to the crank and one of the arms.

9. In a card index drawer, the combination of a drawer, bottom plates to the drawer spaced apart, vertically slotted plates attached to the respective ends of the drawer and extending between the bottom plates, a rock-shaft in the plane of the bottom plates 95 and journaled in the end plates, a flat locking bar having journals traversing the slots and rotative therein, said bar being below the plane of the upper surface of the bottom plates when lowered, arms rigidly attached to the rock-shaft and having slots engaged by the journals of the bar, a knob having a shank journaled in the drawer end, a crank on the shank, a rod connecting the crank and one of the journals of the bar, and interlocking forked members on the shank and bar respectively to rotate and hold the bar.

10. In a card index drawer, the combination of a drawer, vertically slotted plates attached to the respective ends of the drawer, a locking bar having journals traversing the slots and rotative therein, a guide on one plate arranged alongside the slot and slidably engaging a flat side of the bar, a rock-shaft journaled in the plates, arms 110 rigidly attached to the respective ends of the shaft and having slots to receive and support the journals of the bar, a knob having a shank rotative in one end of the drawer, a crank on the shank, a rod connecting the 115 crank and one of the journals on the bar, and interlocking forked members respectively and rigidly attached to the shank and bar whereby the bar is turned and held when in raised position.

11. In a card index drawer, a card locking member centrally and longitudinally located at the bottom thereof, means for vertically

raising the locking member, and means for rocking the member on its axis while in such raised position.

12. In a card index drawer, a card locking member oblong in cross section and located longitudinally in and below the plane of the bottom thereof and vertically and rotatively adjustable therein, means for vertically raising the locking member, and means for par-

tially rotating the same while in such raised position.

In testimony whereof I affix my signature in presence of two witnesses.
